UNITED STATES PATENT OFFICE.

JOHN H. ELPASS, OF PUEBLO, COLORADO, ASSIGNOR OF ONE-HALF TO
ROBERT HUGHES, OF DENVER, COLORADO.

PULVERIZING-MILL.

SPECIFICATION forming part of Letters Patent No. 651,798, dated June 12, 1900.

Application filed December 18, 1899. Serial No. 740,800. (No model.)

To all whom it may concern:

Be it known that I, JOHN H. ELPASS, a citizen of the United States of America, residing at Pueblo, in the county of Pueblo and State 5 of Colorado, have invented certain new and useful Improvements in Pulverizing-Mills; and I do declare the following to be a full, clear, and exact description of the invention, such as will enable others skilled in the art 10 to which it appertains to make and use the same, reference being had to the accompanying drawings, and to the letters and figures of reference marked thereon, which form a part of this specification.

15 My invention relates to improvements in pulverizing-mills more especially adapted for use in the reduction of mineral-bearing rock to the degree of comminution or fineness required to permit the separation of the mineral values from the gangue, my object being 20 to provide an apparatus of this class which shall be comparatively simple in construction, economical in cost, and reliable, durable, and efficient in use; and to these ends the invention 25 consists of the features, arrangements, and combinations hereinafter described and claimed, all of which will be fully understood by reference to the accompanying drawings, in which is illustrated an embodiment thereof. 30 In the drawings, Figure 1 is a side elevation of my improved mill. Fig. 2 is a top or plan view of the same. Fig. 3 is a section taken on the broken line X X, Fig. 2. Fig. 4 is a sectional view illustrating a detail of construction. Fig. 5 is a plan view of the same. 35

Similar reference characters indicating corresponding parts in these views, let the numeral 5 designate a base-plate upon which are mounted two sets of upright posts 6 and 40 7, respectively. The posts 6 are located at the outer edge of the base-plate, while the posts 7 are located near the center of the plate. The two sets or series of posts 6 and 7 are equal in number and arranged in pairs, 45 one post 6 and one post 7 forming a pair in which are slidably mounted boxes 8 and 9, in which are journaled the extremities of a horizontal shaft 10, to which is made fast a pulverizing-roll 12, provided with a depend- 50 ing hardened tire or wearing part 12^a, attached to the inner body portion 12^b by lock-

ing-keys 13. The journal-boxes 8 and 9 are each engaged by two coil-springs 14, one being located above and the other below the box. The lower spring engages a stationary 55 support 15, fast on the post and preferably formed integral therewith. The upper extremity of the inner spring is engaged by a movable block 16, slidably mounted on the post and engaged by a tension-screw 17, passing through the cap 18 at the top of the post. The upper extremity of the screw is provided with a hand-wheel 19 for convenience of adjustment. Hence the shafts 10 and their supporting-rolls 12 are held in position by a yielding pressure controlled by the tension-screws. 60

Located between the inner series of posts 6 and the outer series of posts 7 is a revoluble mortar 20, whose bottom is provided with a detachable hardened bed-plate 21, which is 70 engaged by the rolls 12 and forms the pulverizing-surface. This mortar is supported from below by conical rollers 22, engaging a track of corresponding shape formed on the bottom of the mortar, whereby there is a perfect rolling contact between the rollers and the mortar, thus reducing the friction to a minimum. The rollers 22 are journaled in boxes 23, mounted on the stationary bed-plate. Externally mounted on the inner series of posts 7 75 80 is a circular guide-track 24, which is engaged by a ring 25, mounted on the mortar by means of brackets 26, carried by the mortar and to which the ring is adjustably attached. The ring 25 is provided with a depending flange 85 25^a, adapted to engage and interlock with any upwardly-projecting flange 24^a, formed on the stationary guide-track. By this construction the mortar is properly centered and made to rotate in a uniform orbit or path. 90

The rotary movement is imparted to the mortar from a gear 27, engaging a large gear 28, fast on the bottom of the mortar. The gear 27 is fast on a shaft 29, to whose outer extremity is attached a pulley 30, which may 95 be connected with a suitable motor (not shown) or other source of power. The shaft 29 is journaled in suitable bearings mounted on the base-plate.

The outer wall of the mortar is outwardly 100 inclined as it extends upwardly from the bed-plate, as shown at 20^a, and is provided

with a horizontal ledge 20°, of considerable width, beyond which is located the screen 29, which may be of any suitable mesh. The inclined wall 20° of the mortar is located beyond the pulverizing-rolls, a space 20° (see Fig. 3) being left in which the rich concentrates accumulate. This feature has been found in practice to be very important.

Surrounding the mortar and arranged to receive the material therefrom as it passes through the screen 29 is a circular amalgamating-trough 31, supported on the posts 6 and provided with an inclined bottom 30° and a discharge-mouth 30°.

15 In the operation of the machine the material to be treated is fed into the mortar by way of a chute 32, the necessary water being supplied by a pipe 33, having depending branches 34. The mortar is rotated through the instrumentality of the shaft 29, the gear-wheel 27, and the gear 28 on the bottom of the mortar. The rotation of the mortar operates the rolls 12, which act on the rock with a crushing and grinding force by virtue of 25 the cylindrical shape of the rolls. When the material has been pulverized to the desired fineness, it passes through the screen 29 into the trough 31 and thence from the machine by way of a discharge-mouth 30°.

30 To the outer posts 6 are attached horizontal frame-bars 37, provided with inward projections 38, whose extremities are slotted, as shown at 38°, to receive depending arms 35, each of which is secured to a projection 38 by means of suitable nuts 36, applied to the threaded portion of the arm both above and below said projection. The lower extremity of each arm 35 is provided with a blade 35°, located in suitable proximity to the ledge of 40 the mortar. Any necessary or desired number of these blades 35° may be employed. They prevent the material from packing on the ledge of the mortar and clogging the screen. These blades occupy an inclined position, as 45 shown in the drawings, and have a tendency to throw the material from the ledge into the mortar, where it is acted on by the rolls until it is properly pulverized to pass through the screen. The mortar is supposed to travel in 50 the direction indicated by the arrows in Fig. 2. By means of the nuts 36 and the slots 38° in the supporting projections 38 the blades 35° may be regulated or adjusted as desired, both as to height and inclination.

55 The bracket 26 is composed of two parts 26° and 26°. The part 26° is attached to the mortar by means of bolts A, which pass through vertical slots formed in the bracket part. The part 26° is provided with a recess adapted to receive a tongue 26° of the bracket part 26°, the two parts being connected by a bolt B, passing through slots formed in one part and entering a threaded opening formed in

the other part. The part 26° is bolted to the ring 25.

Having thus described my invention, what I claim is—

1. In a pulverizing-mill the combination of an outer and an inner series of posts, shafts journaled in these posts, pulverizing-rolls fast on the shafts, an annular revoluble mortar located between the two series of posts, a circular guide-track mounted on the inner series of posts, a ring mounted on the mortar and engaging said guide-track, conical rollers located underneath the mortar and engaging a track of corresponding shape formed on the bottom of the mortar, a gear attached to the bottom of the mortar outside of the roller-track, and an operating-gear meshing with 75 the gear on the mortar.

2. In a pulverizing-mill the combination with a suitable supporting-frame, of an annular revoluble mortar, a circular guide-track mounted on the frame and surrounded by the inner wall of the mortar, a ring mounted on the mortar and engaging said track, and pulverizing-rolls coöperating with the mortar.

3. The combination with a suitable supporting-frame, of an annular revoluble mortar, conical rollers supporting said mortar from beneath, a guide-track attached to the frame and surrounded by the mortar, a ring mounted on the mortar and engaging said track, and pulverizing-rolls coöperating with 95 the mortar.

4. The combination with a suitable supporting-frame, of an annular revoluble mortar, a circular guide-track mounted on the frame and surrounded by the mortar, a ring adjustably mounted on the mortar and engaging said guide-track, and pulverizing-rolls coöperating with the mortar.

5. The combination of an inner and an outer series of posts, an annular revoluble mortar located between the two series of posts, shafts journaled in spring-supported boxes mounted on the posts, pulverizing-rolls fast on the shafts and engaging the mortar, a circular guide-track mounted on the inner series of posts, a ring mounted on the mortar and engaging said track, the ring and the track being provided with interlocking flanges, an annular amalgamating-trough surrounding the mortar and adapted to receive the discharge from the mortar, conical rollers engaging a corresponding track formed on the bottom of the mortar, a gear fast on the bottom of the mortar, and an operating-gear engaging the mortar-gear.

In testimony whereof I affix my signature in presence of two witnesses.

JOHN H. ELSPASS.
